COMBINED TAPE AND THREAD PACKAGE

William R. L. McBee, South Willington, Conn., assignor to The Gardiner Hall Jr. Company, South Willington, Conn., a corporation of Connecticut

Application November 21, 1931, Serial No. 576,567

14 Claims. (Cl. 206—47)

This invention relates to packages for sewing materials, and more particularly to a combined package containing both a length of the material to be sewn and a sufficient quantity of the proper thread for performing the sewing operation.

Since time immemorial sewing materials such as tape, braid, ribbon, lace and the like, and the thread with which these materials are sewn, have been manufactured and sold with their complementary functions in mind, and yet, as far as applicant is aware, these two classes of goods have never been combined in a common package for display and sale purposes until the invention disclosed in applicant's co-pending application, Serial No. 521,585, filed March 10, 1931, of which this is an improvement.

It had formerly been the custom, when buying sewing materials of this nature, for the purchaser to first select the tape or other material to be sewn, and to then attempt to "match" it as to color, quality, strength, and other characteristics, with a suitable thread. Very often this necessitated two independent transactions, either at two different places in the same store, or at two separate stores, and was universally a source of annoyance to both seller and purchaser due to the difficulty of matching these materials. Furthermore, the purchaser was usually forced to buy a spool of thread containing much more thread than was actually necessary to sew the specific length of material, an obviously uneconomical situation.

It is therefore one of the objects of the present invention to provide a novel combined package for containing both a length of material to be sewn and the proper length of a suitable thread for performing the sewing operation.

Another object is to provide an improved combined package containing both material to be sewn and the thread therefor which package displays the goods in an attractive manner and renders unnecessary the objectionable practice of "matching."

A further object is to provide a novel package of the type described wherein the board or card of the material to be sewn and the spool of thread therefor are secured together and maintained in a substantially unitary assemblage by the provision and use of novel securing means which may be easily and economically manufactured independently of the other elements of the package.

Still another object is to provide a combined tape and thread package wherein the board or

holder of the material to be sewn and the spool of thread are removably secured to one another for display and sale purposes by one or more novelly constructed securing members.

A still further object is to provide a package of the character described comprising a board or card of the material to be sewn, a spool of thread and novel securing means for maintaining said board and spool in a unitary relationship, which elements may be separately manufactured and assembled to form a unitary package, quickly, efficiently and economically.

These and other objects will appear more fully from a consideration of the detailed description of the invention which follows. Although several embodiments of the invention have been described and illustrated in the accompanying drawing, it is to be expressly understood that this drawing is for the purpose of illustration only, and is not to be construed as a limitation of the scope of the invention. Reference should be had for this latter purpose to the appended claims.

In the drawing, wherein like reference characters indicate like parts throughout the several views:

Fig. 1 is a plan view of a combined tape and thread package illustrating one embodiment of the present invention;

Fig. 2 is a longitudinal sectional view of one end of a package constituting another embodiment of the invention; and

Figs. 3, 4 and 5 are similar perspective views, with certain parts removed, of the extremities of three other packages illustrating further embodiments of the present invention.

In the form shown in Fig. 1, a length of the material to be sewn, indicated at 6, which may be tape, braid, ribbon, lace, or other similar material, is wound in the usual manner upon a board or card 7 substantially rectangular in shape. As shown, material 6 is wound lengthwise of the board 7, but it will be understood that if desired it may be wound in any other desired manner.

For any given material 6 there is always a certain thread the color, strength and quality of which best fits it for use with that particular material. Accordingly, a length of thread 8 of the proper characteristics and in a quantity sufficient, but not excessively oversufficient, to sew the material 6, is wound upon a spool 9 of any desired material and form, the length of which is substantially equal to the width of card 7. It will be noted that the spool of thread thus

formed is not necessarily cylindrical in shape, but is so formed that its thickness does not materially exceed that of board 7 together with material 6 wound thereon. Obviously, the same 5 result might be obtained by thickening the board or card 7 and using an ordinary cylindrical spoil.

In order that the spool of thread and the board or card of material may form a unitary package for shipping, display and sale purposes, 10 suitable means are provided for detachably securing these elements together in substantially unitary relationship. The means provided for this purpose must not only be adequate to prevent the spool and board of material from becoming separated during shipment and subsequent handling, but must also be readily detachable so that the elements may be easily separated for use by the purchaser. In the embodiment 15 illustrated, the securing means comprise a pair of specially shaped wire securing members 10 each of which is provided with a pair of parallel arms 11 spaced apart and connected together at one of the extremities thereof. Wire members 10 may be made of any desired form 20 of wire, either round or flat, and economically manufactured by stamping from a blank and bending to the desired shape. While arms 11 may be made straight, if desired, they are each 25 preferably provided with a crimped portion 12, and made with a resiliency or springiness which 30 opposes separation thereof.

In assembling the package and securing the 35 spool 9 to board or card 7, one of the arms 11 of each of members 10 is inserted within the bore or interior of spool 9, while the other arm 11 of each of said members is passed between one of the surfaces of board 7 and the material 6 which is wound thereon, at a point adjacent 40 the top of said board. The arms of members 10 are thus inserted from opposite sides of spool 9 and board 7, and crimped portions 12 are made sufficiently long that the corrugations of the 45 members thus inserted from opposite sides of the package interengage or interlock with one another so as to increase the resistance to their separation and withdrawal from the assembled position. Since securing members 10 are 50 preferably made with a certain spring so that the two arms 11 resiliently oppose any separation thereof, it will be evident that spool 9 is held to board 7 by the resilient gripping action of the arms 11 of members 10, and that accidental displacement of said spool sideways relative to the card is opposed by both the frictional engagement between crimped portions 12, the interior of spool 9, the surface of board 7 and the underside of material 6, and by the interlocking engagement of said crimped portions. This frictional and interlocking engagement, however, is 55 not so great as to prevent the purchaser from readily sliding spool 9 laterally in either direction with respect to board 7 when removing the spool of thread for use in the sewing operation.

The assembly of board or card 7 with the material 6 wound thereon, and its associated spool 9 of thread 8 may then be enclosed in a suitable wrapper 13 to form a compact, unitary package. Wrapper 13 is preferably made of some transparent material, such as cellophane, in order that the goods within may be well displayed to the eye of the prospective purchaser. If desired, a label 14 may be included in the package carrying the usual identifying mark of the manufacturer, or manufacturers if the ma-

terial 6 and thread 8 are manufactured separately, and other usual printed matter descriptive of the material enclosed.

In the embodiment shown in Fig. 2, spool 9 is secured to board 7 by a single securing member 15 of somewhat different construction than the two members 10 employed in the embodiment of Fig. 1. As shown, member 15 is provided with one arm 16 which may be provided with a crimped portion 17, similar to arm 11 and crimped portion 12 previously described, which arm is engaged between the surface of board 7 and the material 6 wound thereon. The other arm 18 of member 15 may be straight and slightly divergent from arm 16, and is provided at its outer end with a portion 19 bent to an acute angle therewith. Arm 18 and bent end portion 19 are adapted to be inserted within the bore or interior of spool 9 from one end thereof with the point of end portion 19 in frictional or digging engagement with the inside surface of said spool. As shown, it will be evident that securing member 15 may be readily placed to secure spool 9 to board or card 7, but that separation of the spool from the board by sliding to the left, as viewed in Fig. 2, will be prevented by the engagement of bent end portion 19 with the interior of said spool, and to the right, will be opposed by the frictional engagement of crimped portion 17 with the surface of board 7 and the underside 105 of material 6. In this embodiment, as in that disclosed in Fig. 1, the arms 16 and 18 of member 15 are preferably made with a spring which 100 resiliently opposes separation thereof.

In Fig. 3, another form of securing member 110 is disclosed, this member 20 having three arms 21, 22 and 23 each having a crimped portion 24. Arms 21, 22 and 23 are preferably formed out of a unitary piece of wire, bent to shape with all arms substantially parallel to one another, 115 and formed with a suitable resiliency so as to oppose separation. Arms 21 and 22 are spaced apart a distance substantially equal to the thickness of board or card 7, and, when the package is assembled, pass between the surfaces of said 120 board and the material 6 wound thereon so as to resiliently grip the board therebetween. Arm 23 at the same time engages the interior of spool 9 in a manner similar to that previously described in connection with the embodiment of 125 Fig. 1. It will be noted that the corrugations of crimped portion 24 of arms 21 and 22 lie preferably in the plane passing through said arms.

In the embodiment of Fig. 4, spool 9 is again secured to board or card 7 by a single securing member 25 having a pair of arms 26 and 27 engaging the interior of said spool, and a third arm 28 being engaged between the surface of board 7 and material 6. In this embodiment, arms 26 and 27, while substantially parallel, are 130 provided with outwardly turned end portions 29, and since arms 26 and 27 are so constructed that they normally resist displacement either toward or away from one another, said end portions have a substantial frictional or digging engagement with the inner surface of spool 8. Arm 28 is provided with a crimped portion 30 in order to increase the frictional engagement between said arm and the surface of board 7 and material 6. When assembling the package disclosed in this 135 embodiment, arms 26 and 27 are initially compressed toward one another so that end portions 29 pass freely within spool 8, and then are allowed to separate to engage the interior of said spool, arm 28 at the same time passing between 140

one surface of board 7 and the underside of material 6.

In Fig. 5, there is disclosed an embodiment somewhat similar to Fig. 1, in that a pair of securing members 10' having arms 11' and crimped portions 12' are utilized, but differing therefrom in that the two arms 11' which engage board or card 7 do not rely upon material 6 for part of their frictional grip, but pass underneath a suitable retaining strip 31 which may be made of paper, or other suitable material, and pasted or otherwise secured along two edges thereof as at 32 to one side of board 7. Arms 11' are thus maintained in the space between strip 31 and the surface of board or card 7.

It will thus be seen that by the present invention there has been provided a new and improved form of package for sewing materials which will greatly simplify the merchandising and sale thereof, and eliminate the difficulty and annoyance incident to "matching" the material to be sewn with a suitable thread. Not only is the combined package herein provided a welcome innovation to the purchaser, but, by its unitary construction in a transparent wrapper, injury to the goods by handling and soiling is avoided, thereby resulting in a saving to the seller. The goods are attractively displayed, and the package is so compact that a saving in display and storage space is obviously effected over the present situation where the material and thread are sold separately. Since the novel form of package protects the spool of thread, an additional saving may be effected in that the spool upon which the thread is wound need not be made of wood or other substantial material as is now the practice, but may be of a comparatively weak material such as paper or cardboard.

It will be obvious that the invention is not limited to the form shown in the drawing, but is capable of a variety of mechanical embodiments. For example, the board or card upon which the material is wound may be of any desired shape other than the rectangular form shown, and other forms of spools may obviously be substituted for the spool illustrated and described. It will also be understood that the board and spool may be made of any suitable material including wood, cardboard and metal. Furthermore, any desired form of securing member which is the equivalent of any of those shown may be substituted therefor, and if desired, two of the members disclosed in Figs. 2, 3 and 4 may obviously be employed instead of one as shown. Various other changes which will now appear to those skilled in the art, may be made in the form, details of construction and arrangement of the parts without departing from the spirit of the invention, and reference is therefore to be had to the appended claims for a definition of the limits of the invention.

What is claimed is:

1. A display and sales package for sewing materials comprising a board-like member having a length of the material to be sewn wound thereon, a spool of thread, and a securing member having a plurality of substantially parallel arms engaging said board-like member beneath the material wound thereon and the interior of said spool for maintaining said elements in substantially unitary relationship.

2. A display and sales package for sewing materials comprising a board-like member having a length of the material to be sewn wound thereon, a spool of thread, and a securing member

having a plurality of arms engaging said board-like member and said spool for maintaining said elements in substantially unitary relationship, one of said arms engaging the interior of said spool and another of said arms being engaged between the surface of said board-like member and the material wound thereon.

3. A display and sales package for sewing materials comprising a board-like member having a length of the material to be sewn wound thereon, a spool of thread, and a resilient securing member engaging both the interior of said spool and said board-like member beneath the material wound thereon and uniting said elements into a substantially unitary package.

4. A display and sales package for sewing materials comprising a board-like member having a length of the material to be sewn wound thereon, a spool of thread, and a securing member having a plurality of substantially parallel crimped arms frictionally engaging both the interior of said spool and said board-like member beneath the material wound thereon whereby said latter two elements are maintained in a substantially unitary assembly.

5. A display and sales package for sewing materials comprising a board-like member having a length of the material to be sewn wound thereon, a spool of thread, and a pair of securing members each having a plurality of arms for uniting said spool and said board-like members into a substantially unitary assembly, one of the arms of each of said securing members engaging said spool from opposite ends thereof, and another arm of each of said securing members passing between the surface of said board-like member and the material wound thereon.

6. A display and sales package for sewing materials comprising a board-like member having a length of the material to be sewn wound thereon, a spool of thread, and means for securing said member and spool together in a substantially unitary package comprising a pair of wire members each having a pair of crimped arms, one arm of each of said wire members engaging the interior of said spool, said arms entering the spool from opposite ends thereof, and the other arm of each of said wire members passing between the surface of said board-like member and the material wound thereon, the crimped portions of said arms being adapted to interengage to increase resistance to separation thereof.

7. A display and sales package for sewing materials having as elements a board-like member on which is wound a length of the material to be sewn and a spool of thread, and a securing member for uniting said elements into a substantially unitary assembly comprising a plurality of arms substantially parallel to one another, two of said arms resiliently gripping one of the elements united by said securing member, and another of said arms being in frictional engagement with the other of said elements.

8. A display and sales package for sewing materials comprising a board-like member on which is wound a length of the material to be sewn, a spool of thread, and a securing member for uniting said board-like member and said spool into a unitary assembly comprising a plurality of arms, two of said arms frictionally engaging the surfaces of said board-like member and resiliently gripping said member therebetween, and another of said arms engaging the interior of said spool.

9. A display and sales package for sewing materials comprising a board-like member on which is wound a length of the material to be sewn, a spool of thread, and a securing member for holding said spool to said board-like member comprising a plurality of arms substantially parallel to one another, one of said arms engaging the interior of said spool, and others of said arms being engaged between the opposite surfaces of said board-like member and the material wound thereon. 5

10. A display and sales package for sewing materials comprising a board-like member having a length of the material to be sewn wound thereon, a spool of thread, and a securing member maintaining said spool and board-like member in a substantially unitary assembly comprising an arm having an end portion adapted to frictionally engage the interior of said spool, and another arm being engaged between the surface of said board-like member and the material wound thereon. 15

11. A display and sales package for sewing materials comprising a board-like member having a length of the material to be sewn wound thereon, a spool or thread, and a securing member maintaining said spool and board-like member in a substantially unitary assembly comprising an arm having an end portion bent to an angle therewith and in frictional engagement with the interior of said spool, and another arm engaged between the surface of said board-like member and the material wound thereon, 20

13. A display and sales package for sewing materials comprising a board-like member having a length of the material to be sewn wound thereon, a spool of thread, and means for maintaining said spool and board-like member in a substantially unitary assembly comprising a multi-armed securing member having one arm frictionally engaging the interior of said spool, and a retaining member secured to said board-like member beneath the material wound thereon, another arm of said securing member being engaged beneath said retaining member. 15

14. A package of tape and thread comprising a card having a substantially flat rectangular portion with tape wound thereon, a spool of thread positioned at one end of said card so that the thread is visible, and means insertable between the card and tape for detachably securing the spool to the card. 20
